UNITED STATES PATENT OFFICE

JAMES FRANCIS KEY, OF PASADENA, CALIFORNIA, ASSIGNOR OF ONE-HALF TO
LEONARD S. LYON, OF LOS ANGELES, CALIFORNIA

NIGHT SIGHT FOR FIREARMS

Application filed June 1, 1929. Serial No. 367,657.

This invention relates to a device for sighting firearms at night.

Heretofore it has been suggested to combine with a firearm a light capable of producing a pencil ray of light parallel with the bore of the firing arm so that the point that the pencil of light strikes will indicate the point where a shot from the firearm will hit. These devices have not gone into extensive use for the reason that in practice, the recoil of a firearm has been sufficient to destroy the filament of the light. It is the primary object of the present invention to provide a night sight for a firearm which will be unaffected by the recoil of the firearm to the end that a night sight for a firearm is provided which may be repeatedly used.

More specifically stated, the object of the present invention is to provide a sight for a firearm which has means for permanently or temporarily attaching the same to the firearm in such a way that the recoil of the firearm places no shock upon the filament of the light of the night sighting appliance.

The invention includes generally two different specific forms of attachment between the night sighting appliance and the firearm itself. In one or the major or preferable form of the invention, the night sighting appliance is so constructed that the firearm may be laid in a groove or other guiding device in the night sighting implement and when fired may recoil away from or separate from the night sighting appliance without placing any recoil or shock upon the appliance. In the other form of the invention, the night sighting appliance is so combined with the firearm as to be at the center of the pivoting recoil action of the firearm so that the shock is not imposed upon the filament of the night sighting appliance.

Various further features, advantages and objects of the present invention will be apparent from the description of a preferred form or example of a firearm embodying the invention. For this purpose there is hereafter described a number of preferred forms and examples of night sighting appliances for firearms embodying the invention. The

description is given in connection with the accompanying drawings, in which

Figure 1 is a plan view of one form of the invention.

Figure 2 is an enlarged plan view partially in horizontal section of the same form of the invention.

Figure 3 is a section on the line 3-3 of Figure 1.

Figure 4 is an elevation mainly in vertical section of a modified form of the invention.

Figure 5 is an elevation of a further modified form of the invention.

Figure 6 is an elevation of a further modified form of the invention.

Referring to the drawings, the appliance of Figures 1 to 3 of the drawings comprises a battery casing 2 and a flashlight casing 3, both of cylindrical form and arranged parallel to each other. The battery casing and flashlight casing are supported by a bracket 4 which is provided between the casings with a firearm barrel rest 5 in the form of a channel iron, the sides of which are adapted to engage the barrel 6 of a firearm 7 (Figure 1). The flashlight casing 3 is welded or otherwise secured to the bracket 4 with relation to the sighting rest 5, so that these elements will be parallel in operation. Each particular type of firearm of course varies in shape of firing barrel, muzzle, etc. and slight alterations are required to adapt the present invention to the different makes and types of firearms.

In the preferred form of the invention, the guiding rest 5 is secured to the bracket 4 by set screws 8 passing through openings 9 which are sufficiently larger than the set screws 8, to permit an accurate alignment between the guide 5 and the flashlight casing 3. Washers or shims 10 are shown between the guiding member 5 and the base bracket 4.

The guiding member 5 is located down between the two casings 2 and 3 in order that the sides of these casings, extending up above the guide 5, may in practice operate as a means for guiding the barrel of the gun down against the rest 5. It will be understood that the gun and the night sighting appliance have no fastening therebetween and may be carried separately at night. The night guiding de-

vice may be grasped in one hand, the gun in the other hand and one quickly laid against the other and the casings 2 and 3 extending upwardly above the rest facilitates the quick bringing together of the firearm and the night sighting appliance.

The battery casing 2 may be of any usual or preferred construction, its sole function being to provide a holder for batteries such as 10 and 11 for energizing the light in the flashlight casing. In the particular form shown, two conventional batteries are illustrated, the forward one of which engages a contact 12 in an insulating body 13 at the forward end 15 of the casing, which contact 12 connects with a wire 14 which leads under the guide 5 to the flashlight casing connecting there with a switch arm 15. The other terminal of the batteries is grounded with the frame. The 20 said second terminal which is usually the shell of the batteries 10 and 11 is grounded to the casing through the spring 16 holding the rear cap 17 to the casing.

The flashlight casing 3 preferably includes 25 an insulating sleeve 18, the forward end of which engages a head 19 rigidly secured to the casing wall 3 by welding, soldering or the like. A pin 20 is provided interconnecting the insulating sleeve 18 and the head 19 30 to insure proper alignment of these elements. The head 19 is threaded to a light paralleling tube or tube casing 21 which is provided with a number of small tubes 22 which serve the function of baffling out all light from the 35 flashlight which fails to come within the certain narrow pencil of light.

The insulating sleeve 18 has a groove therein receiving a lens 23, the purpose of which is to parallel the rays of light emitted from an 40 incandescent bulb 24. A ring 25 is indicated against which the lens is pressed. The incandescent bulb 24 is mounted by a chuck member 26 which has an accurate fit in an end groove 27 in the sleeve 18. The chuck 45 26 is provided with a bore 28 having an annular shoulder 29 against which a ring 30 is pressed, which ring is secured to a second ring 31 which carries the bulb 24. Adjusting screws 32 are provided for properly aligning 50 or positioning the incandescent bulb 24 in the chuck 26. By this means a mounting is provided for the light which will insure the light being accurately positioned in the casing.

The ring 30 is prevented from rotating in 55 the chuck by a pin 33 engaging the chuck and ring. The end contact of the incandescent bulb 24 is engaged by a plate or disc 34 which is yieldingly urged thereagainst by a coil spring 35 in an end cap 36. The end cap 36 60 is indicated as threaded to the flashlight casing 3. The space inside of the coil spring 35 provided room for storing a spare incandescent bulb 37 and a mounting ring.

Switch means are provided for the incandescent bulb, as best illustrated in Figure 3,

said switch means comprising the spring wire 15 connected with the lead 14 from the battery terminal, the free end of which spring wire 15 is adapted to be pressed by an operating button 16^a against the free end of a second contact of spring wire 17^a which leads as shown in Figure 1, to the sleeve of the incandescent bulb 24 and hence to the filament thereof. It will be seen that the end terminal of the incandescent light is grounded to the frame.

With the night sighting appliance for a firearm thus described, very accurate night shooting is possible. By laying the bore of the firearm in the guiding groove 5, it has been found that very inexperienced people may at night make a better firing record than experienced marksmen can accomplish in the daytime. Moreover, the appliance may be repeatedly used. It will be seen that when the firearm 7 recoils on account of the discharge of a shot, the barrel kicks upwardly and away from the sighting appliance without imposing any shock thereon. Thus the appliance may be repeatedly used.

Now referring to the form of the invention shown in Figure 4, this form is for use with a different shape of firearm, such as an automatic pistol which does not possess a barrel of sufficient length to be fitted into the guiding channel rest 5 of the previous form of the invention. This form of the invention is also so constructed that the night sighting appliance and firearm are connected together so as to be held by a single hand and are arranged so that they will not separate themselves entirely upon each shot.

In this form of the invention, a casing 40 is provided for batteries 41, one terminal of which is connected with the base by a lead 42 with the base terminal of an incandescent bulb 43. The incandescent bulb 43 is mounted in a tube 44 which is provided with a plurality of baffles 45 for blocking out those rays of light which fail to align themselves in the desired pencil form. A lens 46 is also provided in the barrel or tube of the incandescent light for assisting in paralleling the light. The tube holding the incandescent light is secured to a bracket 47 which is suitably shaped to engage certain faces on an automatic pistol, indicated in dotted lines at 48, so that when the said pistol is engaging these faces, the line of fire of said pistol is accurately parallel to the pencil line from the bulb 43. In the particular form shown, the front face of the handle, bottom of the trigger, guard and a portion of the barrel are contacted by a bracket 27. A stirrup 49 is hinged to the bracket which passes over the top of the pistol to prevent the parts entirely separating in use.

With this form of invention, the firearm may be grasped as usual, with one hand. This hand will clamp the bracket 43 against

the pistol and properly align these parts. The hand will also operate then as a spring holding the night sighting appliance to the firearm. When the firearm is discharged, it 5 will recoil away from the night sighting appliance without placing any shock thereon. The hand will operate to absorb the recoil so that when the limit of motion is reached, which is governed by the stirrup 49, no appreciable shock is placed upon the night sighting appliance but the parts are merely held from falling apart. The hand may then quickly restore the night sighting appliance of the firearm into the registered position and the 10 apparatus is found ready for further discharges.

Referring to Figures 5 and 6, forms of the invention are shown in which there is a permanent attachment between the flashlight 20 casing and the firearm. In these forms of the invention, in order to prevent the recoil of the firearm from destroying the filament of the flashlight, advantage has to be taken of the fact that the recoil of the firearm is a pivoting action which takes place therefore about a center. By locating the filament of the flashlight at the axis of this pivoting action or by connecting the flashlight with a part so positioned, a permanent connection 25 may be made between the firearm and the flashlight without the recoil of the firearm destroying the filament of the light.

In Figure 5 the firearm 50 is shown as pivoted at 51 to a bracket 52 which has two 30 clamping parts 53 and 54 so constructed that they are adapted to be clamped around a bar. For example, this form of the invention is especially suitable for use on motorcycles wherein the parts 53 and 54 are clamped 35 around the handlebar of a motorcycle. A clamping screw 55 is indicated for holding the parts in position. The pivot point 51 must be located substantially at the center of recoil action of the pistol 50 in order that the 40 shock of recoil will not be placed upon the bracket 52. The bracket 52 is made to mount the flashlight 56 which serves as the sighting device and the top of the flashlight casing 56 is so shaped as to bear against the guard 45 57 of the trigger or some other portion of the pistol 50 in order to bring these parts into predetermined position.

In Figure 6 the flashlight 58 is indicated as 50 constituting an integral part of the pistol 59 with the bulb of the flashlight located at the exact center of the recoil action.

While the particular forms of the invention herein described are well adapted for carrying out the objects of invention, various 60 changes and modifications may be made without departing from the invention and the invention includes all such changes as come within the scope of the appended claims.

I claim:

65 1. A night sighting device for a firearm

comprising, a source of light, means for emitting the light from said source as a narrow ray, and a firearm rest constructed to register the barrel of the firearm with said narrow ray when the firearm is engaging said rest, 70 said rest being constructed so that the firearm will separate from the rest when recoiling without imposing a substantial shock on the rest.

2. A night sighting device for a firearm 75 comprising, a source of light, means for emitting a light from said source as a narrow ray, a rest connected with said means for engaging a firearm, said rest being constructed to register the firearm barrel with the ray of 80 light, said rest further being arranged so that a firearm engaging the rest on recoiling will separate therefrom without imposing any substantial shock on the rest, and means for guiding the firearm barrel into engagement 85 with said rest.

3. A night sighting device for a firearm comprising, a battery casing and a light casing connected together, the light casing being provided with a lens and means for emitting only such light from the casing as occupies a narrow ray, a firearm barrel rest connected to said light casing in such manner that a firearm barrel engaging said rest will be registered with the ray of light from said casing, said rest being shaped so that the firearm barrel on recoiling will separate from the rest without imposing a shock thereon.

4. A night sighting device as in claim 3 90 in which the battery and light casings provide guiding means for guiding the firearm barrel towards the rest.

5. A night sighting device for a firearm comprising, a flashlight including a bulb, means for emitting the light as a narrow ray, 100 a chuck mounting the bulb, means for aligning said chuck in predetermined positions in the flashlight, and a firearm rest attached to said casing in such manner that a firearm engaging said rest will have its barrel registered with the ray of light from said casing, 105 said rest further being arranged so that the recoil of the firearm will permit the firearm to separate from the rest without the recoil shock being imposed thereon.

Signed at Los Angeles, California, this 110 23rd day of May, 1929.

JAMES FRANCIS KEY.
